UNITED STATES PATENT OFFICE.

WINFIELD HANCOCK YOST, OF MONTREAL, QUEBEC, CANADA.

DRAFT RIGGING.

Application filed November 5, 1923. Serial No. 672,835.

This invention relates to draft riggings for railway cars and the like to cushion the shocks and bumps due to the relative movement between cars and the draft strains.

5 Various types of riggings devised have included those employing wedge mechanism calculated to absorb the shocks and those employing lever mechanism and the present invention appertains particularly to a draft 10 rigging embodying both lever and wedge mechanisms.

As will be well understood, owing to the exigencies of car construction, only a certain degree of coupler travel is permitted and 15 consequently with this prescribed travel as the controlling factor, great difficulty has been experienced in devising a draft rigging capable, without undue weight and mass of material, of absorbing the great shocks incident 20 to the relative movement of rolling stock, and one capable of operating in such a manner as to provide a comprehensive and all absorbing cushioning function initiated in a smooth easy manner and with an immediate 25 free and non-sticking release action.

In the ordinary wedge or low velocity type of draft rigging the car receives a considerable initial shock upon movement and 30 the direct wedge resistance during the stroke of the rigging produces an uneven, choppy action resulting in a jolting absorption of the shocks and undue wear upon the rigging and car. On the other hand the lever or 35 high velocity type of draft rigging as heretofore constructed produces what may be termed a "flash" action in that the levers immediately respond to the shock movement to avoid initial shock but lack the full body 40 resistance requisite for the persistent cushioning action highly desirable in a draft rigging and as a result the shock absorption ceases causing damage to the draft rigging and car.

45 With the above defects in mind an object of my invention is to co-ordinate wedge and lever mechanism in a draft rigging so that under load a lever action is inaugurated and takes up the initial shock, subsequent adequate cushioning resistance being set up by 50 wedge mechanism brought into action by the lever mechanism, the rigging being characterized by the action of the levers in proportionately transferring increasing load to 55 the wedge mechanism so that a portion of the energy in the moving parts of the rig-

ging is utilized to create resisting power therein, thus in the first instance avoiding initial shock and in the second instance producing a smoothly graduated resistance 60 with a persistent cushioning function.

As hereinbefore stated difficulty has been experienced in producing a draft rigging mechanism of the desired degree of flexibility for handling initial as well as sustained loads, within the prescribed limits and without undue weight and mass of material and it is therefore a further object of my invention to produce a draft rigging wherein the load absorbing mechanism is 70 independently active on opposite sides of the rigging whereby the separate and independently acting absorbing units produced lend themselves to a most efficient distribution of strain throughout the structure and avoid 75 the reactive effect of augmentation of strain exerted at one side of the rigging by that exerted at the opposite side and the consequent concentration of combined strain upon certain points of the rigging.

80 Another object is to still further efficiently distribute the strain sustained by the draft rigging by an unique arrangement and division of the wedge surfaces throughout each independently active side of the rig- 85 ging.

85 A further object of the invention, relative to the combination of lever and wedge mechanism, is to provide a lever mechanism which initially acts upon the wedge mechanism differentially in proportionately transferring an increasing load to the wedge mechanism and subsequently discontinues its differential action to effect a simple leverage upon the wedge mechanism to finally 95 stabilize the absorbing action.

90 Still further objects and features capable of advantageous use in draft riggings generally, will be hereinafter more fully described in the following specification and 100 particularly pointed out in the appended claims.

For full comprehension, however, of my invention reference should be had to the accompanying drawings forming a part of 105 this specification, in which the same reference characters indicate the same parts and wherein:

110 Fig. 1 is a horizontal section of my improved draft rigging with the mechanism in normal position, the section being indicated by line 1-1 Fig. 4;

Fig. 2 is a view similar to Fig. 1 and showing the mechanism under compression;

Fig. 3 is a longitudinal vertical section on line 3—3 Fig. 1, omitting the draft bars of 5 the car;

Fig. 4 is a cross-section on line 4—4 Fig. 1, omitting the draft bars of the car;

Fig. 5 is a perspective view of the casing partly broken away to expose the interior;

10 Figs. 6 and 7 are perspective views of the friction member viewed in opposite directions;

Figs. 8 and 9 are perspective views respectively showing the inner and outer 15 faces of one of the wedge members;

Fig. 10 is a bottom plan view of the follower;

Fig. 11 is a cross-section of the follower on line 11—11, Fig. 10;

20 Fig. 12 is a plan view of the central lever; and

Fig. 13 is a plan view of the outer lever.

Referring now to the drawings, 2 indicates the side sills of a railway car which 25 carry the draft lugs arranged at 3 as usual in opposed pairs on opposite sills and spaced longitudinally of the car.

My improved draft rigging, disposed between the opposed pairs of draft lugs, comprises 30 an outer abutment member 4, an inner friction member 5, a wedge member 6 interposed between the members 4 and 5 and lever mechanism 7 interposed between the wedge and friction members and a follower 8, the 35 operative association of these members being influenced by coiled spring 9 (partly shown in dotted lines) and tie bolts 10 and the assembly embraced by the yoke-like draw bar 10^a.

40 The opposing surfaces of friction member 5 and wedge member 6 are in plane frictional relation while the opposing surfaces of members 4 and 6 respectively, present correspondingly inclined surfaces acting to 45 translate a longitudinal relative movement of these members into an inwardly or transverse movement of the wedge member against the inner friction member.

50 The lever mechanism 7 bears between the follower and the absorbing mechanism which includes the friction and wedge members, the lever mechanism fulcruming upon the wedge member so that when the follower moves under the impulse of the draw bar

55 A the lever mechanism first moves the wedge member longitudinally with a consequent transverse movement into frictional engagement with the inner friction member, the retardation of the wedge member due to its 60 engagement with the friction member causing the lever mechanism to swing and exert a leverage upon said friction member to move the latter longitudinally against the transverse pressure of the wedge member. Continued inward movement of the follower

causes the lever mechanism to force the friction member longitudinally inwardly against the spring and transverse pressure of the wedge member, the lever bearing point upon the friction member shifting to effect 70 an increasing leverage upon the friction member. The energy set up in the draft rigging by the differential leverage and the proportionately increasing transverse tightening of the wedge member against the friction member due to the increasing force upon the lever mechanism and its leverage exerted thus utilized to create a great amount of reactive friction for resisting compressive stresses, the cushioning action being 80 smooth and competently absorbing throughout as the lever action is timely effective to take up sharp initial buffing shock while the proportionately increasing frictional action builds up capably sustaining resistance. 85

By reference to Figs. 1 and 5 it will be seen that the abutment member 4 is preferably made in the form of a rectangular casting abutting at one closed end against one set of draft lugs and extending forwardly therefrom to a point spaced from the other set of lugs against which latter the follower 8 abuts in the normal released position of the rigging. The follower opposes an open end of the casing and centrally 90 within the casing is the friction member 5 consisting of plates of less length than and disposed towards the sides of the casing in longitudinal line therewith and a joining web 11 at the forward ends of the plates, the spring 9 bearing between the inner side of the web and the closed end of the casing. A floating wedge plate 6 is disposed parallel to and between each friction plate and the adjacent side of the casing, the opposing 95 surfaces of the friction and wedge plates presenting plane frictional areas, said areas being formed to present co-acting longitudinal concavities and convexities 12 to prevent lateral displacement and maintain the 100 members in proper longitudinal alignment with themselves and the casing and so ensure efficient and precise frictional engagement. In the preferred form the positioning formation is secured by transversely inclining the opposing frictional surfaces as 105 seen particularly in Figs. 4, 6 and 8.

The opposing surfaces of wedge plates 6 and casing 4 are formed with transverse ribs 13 and 14 respectively, with opposed 110 inclined wedge surfaces 15 facing longitudinally of the casing, being inclined inwardly away from the open end of the latter. In the preferred form there is a series of the lugs spaced longitudinally at each side 115 of their respective carrying member, the lugs being spaced longitudinally and of substantially frusto-conical form in cross-section. In assembling the side wedge plates 120 are disposed so that their outer ends are 125

spaced from the open end of the casing, the lugs of the plates interdigitating with the lugs of the casing as shown in Fig. 1, the inner end of each wedge plate being inclined 5 from side to side at 16 to co-operate with a corresponding wedge incline 17 extending from side to side of the casing. The tie bolts 10 extend loosely centrally between the lugs located at opposite sides of the members, 10 the forward ends of the bolts being secured to the follower and the inner ends of the bolts, after passing loosely through accommodating openings 18 in wedge inclines 16 and 17, are provided with nuts 19, spaces 15 20 being provided at the rear of the wedge inclines 17 of the casing to accommodate the necessary rearward movement of the rear ends of the bolts in the movement of the follower.

20 The just described arrangement of wedge surfaces, spreading same in distinct units throughout the surface of the wedge members so distributes the strain sustained thereby as to secure the maximum wedging 25 force without undue localization of stress at any one point thus enabling the members utilized to be constructed with a minimum weight and mass and thereby facilitating the production of an efficient rigging within the prescribed compass allotted to such rigging. In furtherance of this purpose the lugs 13 at each side of the wedge plates are joined by a longitudinal rib 21 which, with the lugs, constitute strengthening ribs for 30 the plates and in like manner, with respect to the casing, the reinforcing effect of the separated lugs 15 is supplemented by the side to side wedge incline 17 and the bolstering support these inclines receive from the ribs 211 produced in the formation on the casing of the accommodating spaces 20 for the travel of the tie bolts. The inclination of the wedge surfaces should be such that the longitudinal reaction of the wedge members will not overcome the bearing force 45 of the levers.

As hereinbefore mentioned the lever mechanism is located between the friction and wedge members and the follower and consists of a central lever 7 extending inwardly 50 from one side of the casing with flanking levers 22 extending inwardly from the opposite side of the casing, each of these levers bearing at one, the outer end 23 upon the forward end of one of the wedge members 55 between which and an inturned flange 24 upon the open end of the casing, this end of the lever is located. Each lever has a curved outer surface 25 bearing against the follower with the opposite surface convexed 60 at 26 and bearing upon the outer surface of the web 11 of the friction member, the levers being adapted to fulcrum upon their outer ends and through the medium of their 65 convexed surfaces 25 causing their bearing

point upon the central friction member to shift with respect to the fulcrum points as the friction member moves thus effecting a differential leverage.

The inner face of the follower 8 is recessed 70 at 27 at the side to receive the flanking levers 22 and at 28 in the centre to receive the central lever 7, the recesses being inwardly curved in the same plane as the surfaces 25 of the levers so that the latter will find an 75 operating pocket therein and be held against lateral displacement. The recesses are supplemented in the latter function by webs 30 extending inwardly from the follower between the levers. The side levers 22 may 80 be made separate but for simplicity I prefer to join them at their outer ends by a cross-piece 31 recessed at 32 for the accommodation of the tie bolt 10 which is likewise accommodated by a similar recess 320 85 in the lever 7.

The radius on which the curvature of the recesses is described is slightly greater than that on which the curved surfaces 25 of the levers are described, for the accommodation 90 of the transverse shifting of the levers during the differential action thereof, thus avoiding the likelihood of the levers binding or seizing in the recesses and promoting a free substantially unretarded action. The 95 levers are maintained and guided in operative position at their inner overlapping ends by the recesses and webs above described, the outer ends of the levers being rounded at 40 to always present an operative bearing surface for the levers upon the ends of the wedge members throughout the swinging movement of the levers in the operative action thereof. The flanges 24 are curved on the underside to intimately overhang the 100 rounded ends of the levers and serve as restricting elements restraining any tendency of the lever ends to withdraw from operative relation with the side wedge members. In this manner the levers are adequately 110 maintained in operative position, the curved engagement thereof with the follower and side wedges enabling the levers to automatically adjust themselves to maintain operative contact with their associated members 115 and compensate for eventual wear between the members, which would otherwise create lost motion interference with the effective action of the rigging.

During the operation of the rigging under 120 buffing stresses and with the moving parts held by the spring in proper contacting relation, see Fig. 1, the draw bar A will move the follower 8 inwardly and cause a slight bodily movement of the levers to initiate a 125 longitudinal movement of the side wedges 6, one wedge being moved by the lever 7 and the other wedge moved by the connected levers 22, the spring meanwhile retarding movement of the central friction member. 130

The co-operating wedge surfaces of the wedges 6 and the casing translate the longitudinal movement of the wedges into a transverse movement, each of the wedges 5 being thus carried into positive frictional engagement with one of the friction plates 5. As the movement of the side wedges is relatively small prior to their engagement with the friction plates the levers are early held from further bodily movement, the inwardly moving follower then causing the levers to operate as levers swinging on their fulcrum ends 23 and bearing upon the central friction member composed of the plates 5 and web 11 thus forcing the friction member into the casing between the side wedges and compressing the spring, the wedge plates at all times bearing with increasing pressure upon the central friction member proportionately to the pressure exerted upon the levers by the follower and the leverage produced by the levers. The central friction member will travel independently of and in the same direction as the side wedges, this unique arrangement of the co-operating parts being of especial benefit in that the reaction of the spring upon the central friction member in initially retarding movement of such member creates a speedy frictional contact therewith by the side wedge members thus initiating the shock absorption immediately upon movement of the draw bar and thereby avoiding free or lost motion of the draw bar, to the end that the full extent of draw bar movement is utilized to obtain a long cushioning or absorbing action.

As the levers swing upon their outer or fulcrum ends the convex faces 26 thereof will cause a shifting of the lever bearing points upon the central friction member, the bearing points moving inwardly away from the fulcrum ends of the levers and effecting a differential action producing increasing leverage with progressing movement of the friction member into the casing. During the action the central friction member will travel a greater distance than the coupler travel so that the frictional resistance set up by and through this movement effects a persistent absorption of the shock irrespective of the spring resistance as the absorption is due to the frictional resistance set up by and between the members when the latter are moved by the coupler or draw bar. The convex surfaces 26 of the levers each terminate in a flat portion 33 which engages the central friction member towards the conclusion of the compressive action of the draft rigging, engagement of these flat surfaces with the friction member eliminating the differential action of the levers which then operate as simple levers for the stabilizing effect to be secured from the use of such levers. However should a force be encoun-

tered greater than the absorbing capacity of the draft rigging the over force causes the follower to engage the open end of the casing whereby the strain is taken up by the car through the casing direct, the working members of the rigging being then inside the casing and thus a solid compression of the spring is avoided and the working parts generally protected from the over strain, see Fig. 2. The presence of the flanges 24 increases the bearing presented at the open end of the casing 4 and serves to reinforce the latter.

As soon as the compressive force ceases the pressure upon the levers and wedges is at zero and the binding friction grip between the side wedge members and central member 5 discontinued. At this time the compressed spring reacts against the central member 5 moving the latter longitudinally towards the open end of the casing and carrying the levers with it slightly away from their engagement at their outer ends with the side wedge members. The practically instantaneous cessation of the binding frictional grip between the side wedge members and the central member and the separation of the levers from the side wedge members reverses this previously active wedge combination into a freer relationship precluding sticking, the progression of the longitudinal movement of the central friction member under the urge of the spring influencing the side wedge members, now relieved from restraint of lever engagement therewith, to slide back over their inclined wedge areas to their normal free floating disposition. The removal of the gripping binding action between the parts at the initiation of the release movement prevents a sticking adherence between the releasing members to the end that such members are smoothly dissociated from their active wedging engagement without the jumpy irregular action heretofore present in draft riggings of prior constructions. During the final releasing travel of the inner member 5 the levers are carried thereby so that their outer ends engage the overhanging flanges 24 at the outer end of the casing and are held thereby from irregular displacement, the levers fulcruming upon these flanges 24 and thereby being caused to swing so that their outer ends swing down into normal engagement with the ends of the side wedges and the inner ends of the levers together with the follower, are returned to normal open position projecting outwardly from the open end of the casing, the flanges 24 serving the two-fold purpose of preventing complete and disrupting travel of the levers out of the casing and automatically causing the levers to regain their operative engagement with the side wedges.

Inasmuch as the wedging action is only present when the rigging is under compression due to either buffing or pulling, the frictional resistance becomes inactive immediately the pressure is removed as the floating wedge members become inactive at that time in so far as their wedging function is concerned and consequently the members are free to permit substantially an instantaneuous release and return to normal position by the expansion of the spring as positive resistance between the parts such as to make them stick, is absent.

During pulling stresses the action will be the same as in buffing with the distinction that the follower will remain stationary while the yoke will move the casing forward, the levers swinging in the same manner as above described with the same action upon the mechanism.

The hereinbefore mentioned restriction in the space available for a draft rigging equipment precludes the use of a single spring of adequate dimensions and consequently the spring usually employed is of inadequate power, being overworked and of insufficient power to return the gear to normal position against active friction and without sticking. This defect is eliminated in the present construction by the absence of active friction as above described whereby the likelihood of sticking retardation in releasing the gear even with inadequate spring equipment, is eliminated. However in order to provide within the prescribed limitations spring equipment which can be calculated to be fully adequate to take care of the accepted stresses without over strain, I have supplemented the spring 9 by a second coiled spring 35 which for economy in space is of smaller diameter than spring 9 for location within the latter and bears between the inner closed end of the casing 4 and the web 11 of the central friction member. Inasmuch as the deflection of the smaller diameter spring 35 is less than that of spring 9 I have compensated for this discrepancy by increasing the number of coils of the smaller inner spring with respect to the larger outer spring 9, the web 11 being centrally recessed at 36 to accommodate the longer inner spring. By this arrangement of a coiled spring enclosing a second coiled spring a compact space economizing equipment is secured and the provision of a longer inner spring approaches equalization of the total deflection of both springs thus ensuring an augmented spring equipment within a given space without likelihood of the spring of smaller diameter being over stressed as would occur were the inner spring of the same length as the outer spring.

It will be noted that the operative elements of the above described draft rigging are the same at each side of the longitudinal

centre line of the gear, that is, either lever 7 or 22 co-operates with its associated wedge 6 which is intermediate its co-operating casing wall and friction plate 5, to produce the combined lever and wedge action described.

Lugs 34 carried by the casing support and guide the friction plates upon their inner side to constitute bearings for the plates, sustaining the inward stresses to which the plates are subjected and guiding the latter in direct longitudinal travel. Each friction plate is flanked upon its inner side by two of the lugs 34, the top and bottom walls of the casing presenting at each side of the longitudinal centre line a pair of these lugs which extend longitudinally in close contact with the top and bottom margins of each friction plate to support same against inward stresses and positively guide the friction plates during their longitudinal travel by preventing lateral shifting or rocking thus making the frictional contact between the friction and wedge members positive at all times.

The presence of the lugs 34 upon the inner side of the friction plates localizes the wedge reaction of each wedge member 6 between the side of the casing and the lugs adjacent thereto, that is to say the reaction to the outward stress of the wedge member upon one side of the casing is supported by the lugs adjacent to such side and is not transferred to the other side of the casing owing to the immovability of the lugs, the reaction set up by the wedge member thus being confined to one side of the longitudinal centre line of the casing. The result is that neither side of the casing is exposed to the reaction of the stress set up by the wedge mechanism at the opposite side as has been the case in prior constructions wherein transverse movement of the friction members was solely limited by the wedge members and consequently the reaction to the wedge member at one side of the casing has heretofore been transferred to the opposite side whereby stress developed at one side has been augmented by the stress developed at the opposite side and the casing thereby exposed to disruptive forces of such degree that only impracticably thickened walls could withstand them.

The described arrangement with the supporting lugs 34 isolates the wedging absorption effected at opposite sides of the rigging and thus produces a dual wedge action independently active at opposite sides of the rigging. The lever at either side is not dependent upon the lever at the other side for the production of the wedge action and consequently should the lever action lag at one side due to slight more or less unavoidable discrepancies in size or form or due to angular force upon the coupler when cars are out of line, the rigging will continue to function with requisite effectiveness, independent wedge absorption of the stresses being ef-

3
fected on opposite sides of the rigging. Furthermore this arrangement most satisfactorily fulfills the desired equalization of strain throughout the structure as, in addition to the hereinbefore described distribution of the wedge surfaces to avoid excessive localization of strain of the active forces as a whole, the dual arrangement just described further effectively apportions the load.

10. What I claim is as follows:

1. In a draft rigging adapted to be compressed for absorbing buffing and pulling stresses, the combination with a casing, of a friction member, a wedge in engagement with the casing and the friction member, a lever for causing relative motion between the wedge and friction member, means supplemental to and immovable with respect to the casing wall for guiding the friction member and means for resisting motion of the parts and returning them to expanded condition after compression.

2. In a draft rigging adapted to be compressed for absorbing buffing and pulling stresses, the combination with a casing, of a friction member, a wedge in engagement with the casing and the friction member, a lever for causing relative motion between the wedge and friction member, means supplemental to and immovable with respect to the casing wall for guiding the wedge and means for resisting motion of the parts and returning them to expanded condition after compression.

3. In a draft rigging adapted to be compressed for absorbing buffing and pulling stresses, the combination with a casing, of a friction member, a wedge in engagement with the casing and the friction member, a lever for causing relative movement between the wedge and friction member, means supplemental to and immovable with respect to the casing wall for centering the wedge and friction member and means for resisting motion of the parts and returning them to expanded condition after compression.

4. In a draft rigging adapted to be compressed for absorbing buffing and pulling stresses, the combination with a casing, of a friction member, a wedge in engagement with the casing and the friction member, a lever fulcrumed within the casing and adapted to cause relative motion between the wedge and friction member, means to keep the fulcrum end of the lever within the casing and means for resisting motion of the parts and returning them to expanded condition after compression.

5. In a draft rigging adapted to be compressed for absorbing buffing and pulling stresses, the combination with a casing, of wedge mechanism, a co-operating lever for acting upon the wedge mechanism during compression, the wedge mechanism providing a fulcrum bearing for the lever during

compression and the casing providing a fulcrum bearing for the lever during the release of the rigging and means for resisting motion of the parts and returning them to expanded condition after compression. 70

6. In a draft rigging adapted to be compressed for absorbing buffing and pulling stresses, the combination with a casing, of wedge mechanism, a co-operating lever for acting upon the wedge mechanism, one end of the lever being disposed between fulcrum bearings therefor disposed transversely of the longitudinal line of travel of the rigging and respectively carried by the casing and the wedge mechanism and means for resisting motion of the parts and returning them to expanded condition after compression and means for holding the parts in assembled operative position. 75

7. A draft rigging adapted to absorb compressive strains due to buffing and pulling and including means for resisting the motion of the parts of the rigging and returning them to expanded condition after compression, a casing, a loosely mounted lever, means presenting a fulcrum bearing for one end of the lever during compression, a projection on the casing and disposed in the path of withdrawal of the fulcrum end of the lever from said fulcrum bearing and 95 means for holding the parts of the rigging in assembled operative position.

8. In a draft rigging, the combination with a casing and mechanism for absorbing compressive buffing and pulling stresses, of 100 a lever for transmitting the stresses to the absorbing mechanism, the absorbing mechanism presenting a fulcrum bearing for one end of the lever during the absorption of the stresses and the casing presenting a fulcrum bearing for the same end of the lever during releasing action of the rigging and means for resisting motion of the parts and returning them to expanded condition after compression. 105

9. In a draft rigging adapted to be compressed for absorbing buffing and pulling stresses, the combination with a follower and wedge mechanism comprising a wedge member and a friction member, of a loosely 115 mounted lever for transmitting stresses to the wedge mechanism, said lever bearing at one end upon the friction member and loosely fulcrumed at its opposite end upon the wedge member, means disposed at the opposite side of the lever to the wedge member for guiding the lever and preventing displacement thereof, and means for resisting motion of the parts and returning them to expanded condition after compression. 120

10. In a draft rigging adapted to be compressed for absorbing buffing and pulling stresses, the combination with a casing, a follower and wedge mechanism comprising a wedge member and a friction member and 130

means for resisting motion of the parts and returning them to expanded condition after compression, of a loosely mounted lever for transmitting stresses to the wedge mechanism, said lever bearing at one end upon the friction member and loosely fulcrumed at its opposite end upon the wedge member during compression and upon the casing during release and means for guiding the lever and preventing displacement thereof.

11. In a draft rigging adapted to be compressed for absorbing buffing and pulling stresses, in combination, a casing, a lever and wedge mechanism at each side of the 15 casing, said casing supporting the inward and outward stresses of the wedge mechanism at each side of the longitudinal central line of the casing and means for resisting motion of the parts and returning them 20 to expanded condition after compression.

12. In a draft rigging adapted to be compressed for absorbing buffing and pulling stresses, in combination, a casing, supporting members carried by the casing and disposed longitudinally in immovably spaced 25 relation inwardly of the casing sides, a lever and wedge mechanism and a friction member at each side of the casing, the wedge and friction members which are at each side of the casing being disposed between the casing side and the adjacent supporting member, and means for resisting motion of the parts and returning them to expanded condition 30 after compression.

13. In a draft rigging adapted to be compressed for absorbing buffing and pulling stresses, the combination with a casing presenting an open end with an inturned projection at such open end of wedge mechanism including a wedge member and a friction member movable longitudinally of the casing, a follower adjacent the open end of the casing, a lever disposed between the follower and wedge mechanism, one end of the 40 lever bearing upon the end of the wedge member therebetween and the inturned projection of the casing and the opposite end of the lever bearing between the follower and friction member, and means for resisting motion of the parts and returning them to expanded condition after compression.

14. In a draft rigging adapted to be compressed for absorbing buffing and pulling stresses, the combination with a casing, of 45 wedge mechanism within the casing and including a longitudinally movable wedge member, the opposing surfaces of the wedge member and the casing wall presenting co-operating wedge surfaces translating the 50 longitudinal movement of the wedge member into a transverse movement of the latter and a longitudinally movable friction member located on the inner side of the wedge member and adapted to have the 55 wedge member bear frictionally thereon dur-

ing the transverse movement of the latter, a lever adapted to transmit longitudinal stresses to the wedge mechanism to move the members thereof longitudinally, the opposing frictional surfaces of the wedge and 60 friction members being formed with longitudinally extending convexities and concavities, a guide upon the casing disposed upon the inner side of the friction member to 65 guide the latter and maintain the frictional contact therebetween and the wedge member, and means for resisting motion of the parts and returning them to expanded condition after compression.

15. In a draft rigging adapted to be compressed for absorbing buffing and pulling stresses, the combination with wedge mechanism and a follower presenting a central curved recess opposed to the wedge mechanism, with similar recesses at opposite sides 85 of the central recess and webs projecting inwardly from the follower between the recesses, of lever mechanism bearing between the wedge mechanism and the follower and including a central lever disposed between 90 the webs of the follower and extending transversely from one side of the rigging and flanking levers on the outer sides of the webs and extending transversely from the opposite side of the rigging, each of such levers presenting a curved surface disposed within one of the recesses of the follower, the curvature of the lever surfaces being described on smaller radii than the curvature of the recesses presented by the follower, 100 and means for resisting motion of the parts and returning them to expanded condition after compression.

16. In a car, the combination with longitudinally spaced draft lugs of a draft rigging including a casing, a friction member, a spring supporting the friction member, a wedge member intermediate the wall of the casing and the friction member, the opposing faces of the wedge member and the adjacent wall of the casing presenting co-operating wedge surfaces and the opposing faces of the wedge member and friction member each presenting a plurality of angularly disposed friction surfaces co-operating with the opposed friction surfaces of the other member, a follower disposed adjacent the open end of the casing and a lever fulcrumed upon the wedge member and bearing between the follower and the friction member.

17. In a car, the combination with longitudinally spaced draft lugs, of a casing disposed between the draft lugs and having one end open, opposite interior surfaces of 125 the casing presenting areas inclined inwardly away from the open end of the casing, wedge members floatably mounted within the casing and presenting areas opposed to and inclined correspondingly to the inclined 130

areas of the casing, a friction member between the wedge members and comprising plates side by side with and in frictional relation with the inner opposing surfaces of the wedge members and a joining web adjacent the open end of the casing, supporting projections upon the casing in supporting relation to the inner surfaces of said plates, a spring bearing between the closed end of the casing and the joining web of the friction member, a follower adjacent the open end of the casing and levers, each lever having a fulcrum bearing upon one end of the wedge members and extending inwardly therefrom between the follower and the friction member, one surface of each lever bearing upon the friction member and the opposite surface bearing upon the follower.

18. In a car, the combination with longitudinally spaced draft lugs, of a casing disposed between the draft lugs and having one open end, opposite interior surfaces of the casing presenting areas inclined inwardly away from the open end of the casing, in-turned projections at the open end of the casing, wedge members floatably mounted within the casing and presenting areas opposed to and inclined correspondingly to the inclined areas of the casing, a friction member between the wedge members and comprising plates side by side with and in frictional relation with the inner opposing surfaces of the wedge members and a joining web adjacent the open end of the casing, supporting projections upon the casing in supporting relation to the inner surfaces of said plates, a spring bearing between the closed end of the casing and the joining web of the friction member, a follower adjacent the open end of the casing and levers, each lever having a fulcrum bearing upon one of the wedge members and extending inwardly therefrom between the follower and the friction member, the open end of the casing and levers, each lever having a fulcrum bearing upon one of the wedge members and extending inwardly therefrom between the follower and

the friction member, one surface of each lever bearing upon the friction member and the opposite surface bearing upon the follower, the fulcrum ends of the levers being rounded and disposed between the wedge members and the inturned projections at the open end of the casing.

19. In a car, the combination with longitudinally spaced draft lugs, of a casing disposed between the draft lugs and having one end open, opposite interior surfaces of the casing presenting areas inclined inwardly away from the open end of the casing, wedge members floatably mounted within the casing and presenting areas opposed to and inclined correspondingly to the inclined areas of the casing, a friction member between the wedge members and comprising plates side by side with and in frictional relation with the inner opposing surfaces of the wedge members and a joining web adjacent the open end of the casing, supporting projections upon the casing in supporting relation to the inner surfaces of said plates, a spring bearing between the closed end of the casing and the joining web of the friction member, a follower adjacent the open end of the casing and presenting curved recesses opposed to the friction member, and levers, each lever having a fulcrum bearing upon one of the wedge members and extending inwardly therefrom between the follower and the friction member, one surface having a shifting bearing upon the friction member and the opposite surface being convexly curved and located in one of the recesses of the follower, the curvature of the last mentioned lever surfaces being described on smaller radii than that of the curvature of the recesses.

In testimony whereof, I have signed my name to this specification, this 30th day of October, 1923.

WINFIELD HANCOCK YOST.
